UNITED STATES PATENT OFFICE.

GUSTAVE LIDSEEN, OF CHICAGO, ILLINOIS.

CAN-COVER LOCK.

Original application filed March 9, 1918, Serial No. 221,421. Divided and this application filed January 12, 1920. Serial No. 350,961.

To all whom it may concern:

Be it known that I, GUSTAVE LIDSEEN, a citizen of the United States, and a resident of the city of Chicago, in the county of Cook and State of Illinois, have invented certain new and useful Improvements in a Can-Cover Lock; and I do hereby declare that the following is a full, clear, and exact description of the same, reference being had 5 to the accompanying drawings, and to the numerals of reference marked thereon, which form a part of this specification.

This invention covers a division of my application for patent for a "lubricating can," filed March 9, 1918, Serial Number 221,421.

The invention relates more particularly to an improved type of a can cover locking mechanism adapted to prevent accidental removal of a can body cover from a 10 can due to jarring or other causes.

It is an object of this invention to provide an improved frictional locking mechanism for a container and the cover thereof.

Another object of the invention is to construct an oil can with a removable spout cap adapted to be locked in position against accidental removal.

It is an important object of this invention to construct a can body and its cover with 15 frictional members which are adapted to be held in frictional engagement against accidental release by means of locking members forming a part of certain of the frictional members.

Other and further important objects of 20 this invention will be apparent from the disclosures in the specification and drawings.

The invention (in a preferred form) is 25 illustrated in the drawings and hereinafter more fully described.

On the drawings:

Figure 1 is a side elevation of a can body and cover equipped with a cover locking mechanism embodying the principles of this 30 invention.

Figure 2 is an enlarged bottom plan view 35 of the can cover removed from the can.

Figure 3 is an enlarged fragmentary top 40 plan view of the can body with the cover removed.

Figure 4 is a side view thereof.

Figure 5 is an enlarged detail section taken on line 5-5, of Figure 1.

As shown on the drawings:

The reference numeral 1, indicates a can body, the upper end of which is rounded to connect with an integral neck or collar 2. The upper margin of the neck 2, is bent outwardly at right angles to form a flange 3, having integrally formed on opposite sides 55 thereof, by cutting away portions of the flange, curved or arc shaped ears or lugs 4. One end of each of the ears 4, is disposed in the plane of the flange 3, and has the end margin of one end thereof curled or bent 60 downwardly to form a hook 5. The other end of each of the ears 4, is depressed or deflected downwardly as denoted by the reference numeral 6. The ears 4, are disposed with the like ends thereof positioned diametrically opposite one another, as clearly 65 shown in Figure 3.

The can cover comprises a cylindrical casing or shell 7, to the upper end of which is rigidly secured by soldering or other suitable means, a passaged outwardly tapering spout or nozzle 8. Integrally formed on the lower end of the casing 7, is a top or cover plate 9, the margin of which is bent downwardly to form a 70 rim 10. Integrally formed on the rim 10, are a pair of inwardly directed oppositely disposed ears or lugs 11, one end of each of which is bent or deflected outwardly, as denoted by the reference numeral 12. The 75 ends of the ears 11, are arranged with the like ends thereof disposed diametrically opposite one another, as shown in Figure 2. Removably seated within the rim 10, of the cover and held in place by the ears 11, is a 80 washer or packing ring 13, made of rubber, felt or any other suitable material.

An oil ejecting mechanism 14, is mounted 85 within the can cover, and is adapted to be operated by an actuating lever 15.

The operation is as follows:

To close the can 1, the cover is placed upon the flange 3, with the cover plate ears 11, registering with the cut-out portions of the flange 3. With the parts in this position the 90 downward bent ends 12 of ears or lugs 11 will lie adjacent to the hooks 5 of the ears

or lugs 4, and there will be sufficient clearance between the two to permit said ends 12 to pass beneath said hooks 5 when the cover is rotated clockwise. Such rotation will 5 cause the ears or lugs 11 to ride beneath the hooks 5, said ears springing downward until their other ends pass said hooks 5, which will occur when a quarter turn has been given, whereupon the free ends of lugs 11 10 will lock behind said hooks 5. In this position reverse rotation is prevented, while further rotation clockwise will be resisted sufficiently effectually to prevent accidental relative movement of the parts, though with 15 sufficient force applied this resistance may be overcome and the parts again unlocked by a further quarter turn.

With the cover locked upon the can body 1, a liquid such as oil within the can may 20 be ejected by force through the spout 8, by first inverting the oil-can and then operating the lever 15, to cause the ejecting mechanism 14, to trap oil in the casing 7, and then force the trapped oil out of the mouth of 25 the spout 8, independently of any flexing of the sides or bottom of the can body 1.

I am aware that numerous details of construction may be varied through a wide range without departing from the principles

of this invention, and I therefore do not 30 purpose limiting the patent granted otherwise than necessitated by the prior art.

I claim as my invention:

1. The combination with a can body and the cover thereof, of frictional members integrally formed on said can body and cover and adapted to engage when the parts are rotated relatively, and hooks formed on one of said sets of frictional members adapted to engage behind the frictional members of the other set to lock the parts against reverse rotation. 35

2. A can, comprising a can body, ears integrally formed thereon each depressed at one end and formed with a hook at its other 45 end, a can cover, and ears integrally formed thereon each depressed at one end, said cover ears adapted frictionally to engage said can body ears and to lock behind the hooks on said latter ears when 50 the parts are rotated relatively.

In testimony whereof I have hereunto subscribed my name in the presence of two subscribing witnesses.

GUSTAVE LIDSEEN.
